UNITED STATES PATENT OFFICE.

EDWARD POELLE, OF ST. LOUIS, MISSOURI.

CLOTHING HOOK.

Application filed November 10, 1921. Serial No. 514,202.

To all whom it may concern:

Be it known that EDWARD POELLE, a citizen of the United States of America, residing at 4036 McPherson Avenue, in the city of St. Louis and State of Missouri, has invented certain new and useful Improvements in Clothing Hooks, of which the following is a specification.

This object of my invention is to make 10 a clothing hook from one piece of metal or composition material. A further object is to make a hook which can be clasped over the top of trousers and which will provide a hook to be selectively positioned over a belt thereby holding the belt and trousers in proper fixed relationship. A further object is to secure the drawers and trousers together and to hook these engaging means over a belt if desired. With this and other 15 objects in view, my invention has relation to certain novel features of construction and arrangements of parts as will be hereinafter pointed out in the claim, described in the specification and illustrated in the drawings, 20 in which

Fig. 1 is a longitudinal sectional elevation of my device and

Fig. 2 is a side elevation of my device.

Numeral 3 designates a strip of metal 30 which is stamped and bent into the conformation shown best in Fig. 1. The upper left portion of the metal strip 3 is bent at 4. The upper right portion of the strip 3 is bent at 5 and the right portion 6 of the strip 3 to the right of the bent portion 4 is made to meet the part 5 of the right portion of the strip 3 in a substantial U shaped portion 7. In the left portion of the

strip 3 is stamped the hole or aperture 8 and the triangular point 9 made to protrude 40 inwardly. The hole 10 is stamped in the right portion of the strip 3 and the triangular point 11 permitted to protrude inwardly. By these means a clamping device is formed having a hook. The right and 45 left portions of the strip 3 are fastened to the trousers or drawers or to both by means of the staggered points 9 and 11. The width between the right and left portions of the metal of the strip 3 is such as is substantially equal to the thickness of the cloth or belt band of the trousers. The U shaped member 7 together with the right portion of the metal strip 3 forms the hook which is positioned over the belt.

What I claim to secure by Letters Patent is:

A clothing hook formed of a single strip of metal stamped and bent into a conformation having two substantially parallel end 60 portions, each portion having a triangular point protruding inwardly toward the other, said points being staggered relative each other and near the free ends of said parallel end portions, one of said parallel end portions being shorter than the other and both having their closed ends bent in arcs, the closed end of the shorter of said parallel end portion being bent substantially parallel to said parallel end portions, the closed 70 end of the longer of said parallel end portions being bent to integrally connect with the closed end of the shorter of said parallel end portions.

In testimony whereof I affix my signature. 75
EDWARD POELLE.
